(57) **CLAIM**

The ornamental design for a shoulder exercising apparatus, as shown.

DESCRIPTION

FIG. 1 is a front perspective view of a shoulder exercising apparatus illustrating our new design;

FIG. 2 is a front elevation view thereof;

FIG. 3 is a rear elevation view thereof;

FIG. 4 is a right side elevation view thereof;

FIG. 5 is a left side elevation thereof;

FIG. 6 is a top plan view thereof; and,

FIG. 7 is a bottom plan view thereof.

The broken line showing of a power cord in FIGS. 1-5, inclusive, is environmental structure only and does not form part of the claimed invention.
